UNITED STATES PATENT OFFICE

93,849

DESIGN FOR A PORTABLE BAR OR SIMILAR ARTICLE

Harry Rodstein and Isidore Nathanson,
Brooklyn, N. Y.

Application February 12, 1934, Serial No. 50,703

Term of patent 3½ years

To all whom it may concern:

Be it known that HARRY RODSTEIN and ISIDORE NATHANSON, citizens of the United States and residents of Brooklyn, New York city, in the county of Kings, and State of New York, have invented a new, original, and ornamental Design for Portable Bars or Similar Articles, of which the following is a specification, reference being had to the accompanying drawing, forming part thereof, in which, Figure 1 is a rear perspective view of the portable bar or similar article, showing our new design and Figure 2 is a front perspective view thereof.

We claim:

The ornamental design for a portable bar or similar article as shown.

Dated February 7, 1934.

HARRY RODSTEIN.
ISIDORE NATHANSON.
